UNITED STATES PATENT OFFICE.

CHRISTIAN AUGUSTUS ALBRECHT, OF BERLIN, GERMANY.

MULTIPLE-MAGAZINE LINOTYPE-MACHINE.

SPECIFICATION forming part of Letters Patent No. 688,812, dated December 17, 1901.

Application filed January 18, 1899. Serial No. 702,580. (No model.)

To all whom it may concern:

Be it known that I, CHRISTIAN AUGUSTUS ALBRECHT, a subject of the King of Prussia, German Emperor, and a resident of Berlin, 5 in the Kingdom of Prussia, German Empire, have invented certain new and useful Improvements in Multiple-Magazine Linotype-Machines, (for which application for patent has been made in Germany on the 26th of 10 November, 1898,) of which the following is an exact specification.

The present invention relates to linotype-machines for different headings in combination with ordinary-text printing, in which for 15 each kind of printing special magazines and keyboards are arranged and in which the types or matrices of all magazines are conducted in the same way to the place of assemblage.

20 The object of my invention is to provide a machine with special type for printing headings in addition to those of the magazine of the standard linotype. The characteristic feature is that my machine having a separate distributing-rail can be connected to a 25 linotype-machine of ordinary kind, the distributing-rail of the additional magazine in combination with the distributing-rail of the standard machine thereby forming one 30 single rail. Further, my machine can be moved away from the standard machine at every instant and connected to a second machine without the work of the first machine being interrupted by its removal. The 35 interchangeable magazine, with its distributing-rail, can be connected to the standard machine by means of a coupling device consisting of studs fixed to the extremities of the transporting-screws of the interchangeable 40 magazine and taking into holes provided in the transporting-screws of the standard machine and of a dovetail-formed connecting-piece fixed to the standard machine adapted to be pushed into a recess suitably provided 45 on the additional magazine. To render the coupling more effective, the standard machine may be provided with a latch, which when the additional magazine stands aside can be laid upon the same, where it suitably reposes 50 in a recess of similar form. All parts of the additional magazine are constructed in such

manner as easily to be coupled to the standard machine.

The magazine which forms the object of my invention is carried by rods, which at their 55 feet are provided with rollers. Thus an easy moving away of the magazine from one machine to another is rendered possible.

In the drawings similar letters denote similar parts throughout the different views, and 60 my invention is represented in connection with a machine having two magazines; but evidently it can also be employed for machines having three or more magazines.

Figure 1 is a front elevation of a linotype-machine and my additional magazine and keyboard coupled to it. Fig. 2 is an end elevation of the machine seen from the right side. Fig. 3 shows a plan section on the line *xx*, Fig. 1. Figs. 4 and 5 are detail views of 70 the coupling device for the magazine. Fig. 6 represents a vertical elevation of the ends of the transporting-screws of both machines before they are coupled, the arrow indicating the manner of coupling them. Fig. 7 is a 75 plan of the parts shown in Fig. 6. Figs. 8 and 9 illustrate in elevation and plan the connection of the transport-belts of both machines.

a is the main frame; *b*, the magazine of channels for the matrices; *c*, the keyboard; *d*, the distributing-rail, each machine having its own distributing-rail, both forming a single one when the additional magazine is coupled to the standard machine. The distributing- 85 rail *d* has the purpose to automatically distribute all of the matrices to the proper tubes or channels in their respective magazines.

d' is a transporting-screw for the matrix of the standard machine as usually employed in 90 linotype-machines.

To this matrix-setting machine is annexed on the right-hand side an additional magazine, the detail parts of which are similar to those of the first machine, the essential feature of it being its capacity of being coupled to the standard machine.

b' is a matrix-magazine; *c'*, the additional keyboard; *d''*, the transporting-screw for the matrix. The magazine as well as the keyboard *c'* are supported by a frame by the rods *e*, adapted to roll by means of rollers *f*. The

- keyboard c' by means of levers is in connection with the matrices accumulated in the channels of the magazine b' , to which constantly new matrices are conveyed by the 5 transporting-screws d' and d^2 . When the keys are pressed down, the matrices become released and in known manner drop upon an endless transport-band h , which under the magazine b is inclined and directed downward, so that the matrices of both magazines can be conveyed to the place of assemblage. The transport-belts h and h' are connected together by the cover h^2 , covering the transport-belt h and having between the belts suitably 10 arranged a bottom part, so that the matrix when arrived at the lowest point of the belt h is pushed upon the bottom of h^2 , then slides along this bottom, and at the other end falls upon the belt h' of the standard machine.
- 15 20 The coupling of the transporting-screws and the additional magazine to the standard linotype is effected by means of studs d^3 , fixed to the extremities of the transporting-screws d^2 , which studs engage with corresponding borings provided in the transporting-screws d' of the standard machine. Of course the coupling can be effected inversely, so that the studs are attached to the transporting-screws d' and engage into holes or 25 recesses provided in d^2 . The head of the rail d^5 is provided with a recess, in form corresponding to a latch d^7 , Figs. 6 and 7, movably fixed to the standard machine and adapted to be laid into the recess of the rail 30 35 d^5 , thereby an effective coupling being obtained. Besides this, in order to secure the machine against lateral displacement the standard machine is provided with a dovetail-formed piece d^4 , which when the additional 40 magazine is pushed against the standard machine enters a recess d^6 of the rail d^5 . Owing to these different couplings the transporting-screws of the interchangeable additional magazine are rigidly attached to the standard linotype. The distributing-rail d of the interchangeable magazine and that of the standard machine are advantageously so beveled that when the machines are coupled together they 45 overlap each other and form one single rail.
- 50 55 As indicated in Figs. 1 and 3, the gearings of the transport-belts h and h' are so formed as to be coupled together easily by means of the coupling device k , which might be of any suitable construction.
- 55 The additional frame b' is suitably provided with locking devices i , by means of which the magazine can be fixed in any desired posi-

tion. It is evident that my improved magazine can be coupled to linotypes with more than two magazines and more than two keyboards. 60

Having thus fully described the nature of this invention, what I desire to secure by Letters Patent of the United States is—

1. In a multiple-magazine linotype-machine, the combination of the standard linotype-magazine b having distributing mechanism including the distributing-rail and assembling mechanism with a suitably-supported additional magazine b' adapted to be coupled to and uncoupled from the linotype-machine and provided with a special keyboard c and a special distributing-rail, the end of said rail and that of the distributing-rail of the linotype-machine being correspondingly beveled so as to overlap each other and to form a single distributing-rail when the linotype-machine and the additional magazine are coupled, substantially as set forth. 65 70

2. In a multiple-magazine linotype-machine, the combination of the standard linotype-magazine b having distributing mechanism including the distributing-rail and assembling mechanism with a suitably-supported additional magazine b' adapted to be coupled to and uncoupled from the linotype-machine and provided with a special keyboard c and a special distributing-rail, adapted to form with the distributing-rail of the linotype-machine one single distributing-rail, studs d^3 80 85 fixed to the transporting-screws d^2 and adapted to take into holes provided in the transporting-screws d' of the linotype-machine, a connecting-piece d^4 fixed to the latter and engaging into a recess of a rail d^5 of the additional magazine, a coupling-piece k allowing to couple the gearing of a conveyer-belt of the standard machine to the gearing of the additional magazine, the whole for the purpose as set forth. 90 95 100

3. In a multiple-magazine linotype-machine, the combination of a standard linotype-machine with an additional magazine b' adapted to be coupled to and uncoupled from the linotype-machine, conveyer-belts h h' , a bridge spanning the space between the two belts h h' and guides h^2 supporting said bridge, substantially as described. 105

In witness whereof I have hereunto set my hand in presence of two witnesses.

CHRISTIAN AUGUSTUS ALBRECHT.
